DIMITRIOS TAIFIRNOPOULOS, OF HOBOKEN, NEW JERSEY.

ROTARY STEAM-ENGINE.

1,119,549.

Specification of Letters Patent.

Patented Dec. 1, 1914.

Application filed May 16, 1914. Serial No. 839,035.

To all whom it may concern:

Be it known that I, DIMITRIOS TAIFIRNOPOULOS, a subject of the King of Greece, residing at Hoboken, in the county of Hudson 5 and State of New Jersey, have invented new and useful Improvements in Rotary Steam-Engines, of which the following is a specification.

The principal object of my invention is to 10 provide a device allowing the utilization of steam for producing a direct rotary movement instead of a reciprocating one, thus eliminating waste of energy and reducing considerably the cost of construction. I am 15 aware that the solution of this problem has been attempted by the construction of steam turbines, but my device is intended to solve this problem in another economical way, combining simplicity of construction with 20 efficiency in operation.

A further object of my invention is to provide a device suitable for direct coupling to 25 rotating shafts such as used in steamships and, by making it adaptable for performing a large number of revolutions within a given 30 space of time, to render it useful for direct coupling with machinery requiring great axial velocity, such as dynamos etc.

I attain my object by the particular arrangement and combination of parts herein- 35 after described and reference will now be had to the accompanying drawings, in which:

Figure 1 is a side elevation of the device 35 in its preferred form. Fig. 2 is a front elevation and Fig. 3 a rear elevation of the same. Fig. 4 is a longitudinal section of the device. Fig. 5 and Fig. 6 are cross sectional views taken on the lines 5—5 and 6—6 re- 40 spectively of Fig. 4. Fig. 7 is a cross sectional view taken on the line 7—7 of Fig. 1 and looking in the direction of the arrows. Fig. 8 is a cross sectional view taken on the line 8—8 of Fig. 1. Fig. 9 is a cross sectional view taken on the line 9—9 of Fig. 4. Fig. 10 is a cross sectional view taken on the line 10—10 of Fig. 4. Fig. 11 is a plan view 45 of part of the device with some parts shown in dotted lines. Figs. 12 and 13 are cross sectional views of the part shown in Fig. 11, taken on the lines 12—12 and 13—13 respectively, of Fig. 11. Fig. 14 is a cross sectional view taken on the lines 14—14 of Fig. 4.

Throughout the separate views the same 55 part is designated by the same reference character.

Referring more particularly to the drawing, 21 designates a base plate and extending upward from same, at the front end, is 60 a vertical support 22, and at the rear end a similar vertical support 23. At the front end of the support 22 there is a chamber 24 threaded at the lower end to receive therein the threaded end 25 of a steam inlet pipe 65 26. Mounted on the top of the support 22 is an oil reservoir 27 communicating with the chamber 24 through an oil bore 28, from where the oil is carried on by the draft of the steam to the spots requiring it. A sub- 70 stantially hollow shaft 29 is journaled into the support 22 and made steam tight by means of a screwed in stuffing box 30. The friction is taken up by a ball bearing 31. The hollow end of the shaft 29 abuts in the 75 chamber 24 of the support 22 affording means for the inlet of the steam from the pipe 26. The rear end of the shaft 29 is taken up by a sleeve 32 carried by the support 23 and made steamtight therein by a 80 stuffing box 33. An oil reservoir 34 and an oil bore 35 provide for the lubrication at this end of the engine. The shaft 29 is full at its middle portion and hollow again from there up to the rear end, where it is closed 85 and ends in claws or clutches such as 36. A recess 37 in the sleeve 32 around the end of the shaft 29 allows the steam to escape through holes such as 39 worked in the shaft 29 and holes such as 40 worked in the sleeve 90 32, into a recess 38 formed in the support 23, wherefrom the steam enters the exhaust pipe 41 giving into the recess 38.

A double expansion (high- and low pressure) cylinder 42 is rotatably mounted on 95 the shaft 29, by means of a sleeve 43 screwed into the cylinder head 44 and the sleeve 32 screwed in the cylinder head 45. The two cylinder heads 44 and 45, and an intermediate partition 46 between the two compartments of the cylinder (high- and low pressure) are kept together by bolts such as 47 and secured by nuts such as 48 on either end. The cylinder casing 49 is in one piece with the cylinder head 44 and the cylinder casing 100 50 is in one piece with the cylinder head 45, hinges such as 51 (Figs. 5 and 6) being formed all about the cylinder casing for

taking up the bolts 47. An outer casing 52 runs around the united double-cylinder 42 to give it a smooth outer surface and to serve as pulley in case of transmission of the power by means of a belt. Within each (the low- and high- pressure) compartment of the cylinder 42 a corresponding piston is rigidly mounted on the shaft 29. The pistons for both the high and low pressure compartments of the cylinder are of substantially the same construction and vary only in their respective sizes and outlet means. They have sleeves such as 53 by means of which they are secured to the shaft 29, heads such as 54, 55, 56 and 57 and shells such as 58. Each of the pistons is divided into two separate chambers divided by partitions such as 59 being substantially at right angles with the sleeve 53, except at two opposite places, where they form a helical line as shown in Fig. 4 in the high pressure piston. The two pistons are so placed in respect to each other that the different parts of the periphery of one piston are exactly at right angles with the corresponding parts of the periphery of the other piston. Therefore the cut through both pistons, in their normal position in respect to each other (from which position they cannot move) shows the helical line of section of the partition in one of the pistons, whereas at the same time the diagonal line of section is shown in the other piston. The helical formation is produced by two shoots or channels at opposite places of the periphery of the pistons, in each piston, having openings such as 61 in the shell 58 of each piston. Each piston has two lugs or bosses such as 62 peripherically opposite on the outer surface of the shell 58 of the pistons, each boss 62 having a channel such as 63 leading from the inlet chamber of each piston into the space between the pistons and the cylinder. In the cylinder casing recesses such as 64 are formed and pivoted to bolts such as 65 passing from one cylinder head to the other, secured there by nuts such as 66 on the outside of the cylinder heads, are valve plates 67 as shown in detail in Fig. 11, fitting exactly into the recesses 64 and made steamtight by tongues such as 68 fitted in grooves at three sides or edges of the valve plates 67 and springs in said grooves, such as 69, tending to push the tongues outward. Other springs such as 70, sunk into the shell of the pistons, tend to push the valve plates 67 out from the recesses 64 and the valve plates 67 are of such dimensions as to form steamtight gates in this their normal position, in the space between the pistons and the cylinder. Springs such as 71 are fitted to the bosses 62 to lessen the force of their impact with the valve plates 67. Holes such as 72 in the shaft 29 and in the sleeves of the pistons 53 afford

an entrance to the steam from the shaft to the inlet chamber of the high pressure piston and an escape of the steam from the exhaust chamber of the low pressure cylinder into the shaft 29. Other holes such as 73 in the piston heads 55 and 56 and in the partition 46 allow the steam to pass from the exhaust chamber of the high pressure piston into the inlet chamber of the low pressure piston. All these holes are so placed in respect to each other in each of the contacting surfaces, that they overlap each other so that there is always at least one pair of corresponding holes opposite to each other, affording a free and unobstructed passage to the steam, as diagrammatically shown in Fig. 9 with respect to another part of the engine. The sleeve 43 ends in claws 74 forming a clutch and a sleeve 75 (Fig. 7) slidable on the shaft 29 longitudinally of the same, is kept from rotating with it by tongs such as 76 extending at both sides of the sleeve 75 into grooves or slots worked in a lever 77 which thereby carries the sleeve 75 with it. The sleeve 75 has claws such as 78 both to the rear and to the front, susceptible of engaging and forming a clutch gear with both the claws 74 on the sleeve 43 (and thereby the cylinder 42) and with another clutch sleeve 79 rigidly mounted on the shaft 29. The lever 77 is made of two legs 80 and 81 united on the top by bolts or screws 82 and pivoted at their lower extremity to two brackets 82 screwed to the base plate 21 by means of a bolt 83. Between the two brackets the base plate 21 is slotted as at 84 (Fig. 4) and a member 85, also pivoted to the brackets 82 by means of a bolt 86, is passed through the slot 84 and fixed to the legs 80 and 81 of the lever 77, by means of a bolt 87 passing through said legs and through the member 85, the latter being pivotable on the bolt 87. To the lower extremity of the member 85 is pivotally connected another member 88, as shown at 89, and the member 88 passes under the base plate 21 to the rear of same, being there curved upward and rearward and having connected to its upper end a ring 90. Through this ring 90 passes an extension shaft 91 having two flanges 92 one on each side of the ring 90, to keep the latter fixedly in its place on the shaft 91. The extension shaft 91 enters the open rear end of the sleeve 32 and ends in claws protruding both forward and rearward, such as 93, and forming a clutch adapted to engage the clutches 36 at the rear end of the shaft 29, on one hand, and, on the other hand, the clutches 94 formed in the inside of the rear end of the sleeve 32. The rear end of the engine is made steamtight by means of a stuffing box 95, fastened to the rear support 23.

The operation of the engine is as follows:

The steam enters through the inlet pipe 26 and the chamber 24 the space A in the shaft 29 and therefrom through the holes 72 the inlet chamber B of the high pressure piston. 5 Therefrom it passes through the channels 63 into the space between the piston and the cylinder, marked C and presses against the valve plates 67, thereby causing the cylinder and the pistons (and with them the shaft 29 on which they are rigidly mounted) to rotate in respect to each other in the directions marked by the arrows, the expansion occurring in the spaces inclosed by the open front of each boss 62 and the nearest 10 valve plate 67 in front of it, whereas in the chamber behind the boss, marked D, compression is created which forces the steam out through the openings 61 into the exhaust chamber of the high pressure piston, here 15 designated by E. From here it passes through the holes 73 into the inlet chamber of the low pressure piston, F and makes again the same circuit through channels 63 into the space C of the low pressure cylinder, then behind the bosses 62 into the spaces 20 D and through the openings 61, always of the low pressure piston, into the exhaust chamber of same, designated G. From here it escapes through the holes 72 in the rear 25 section of the shaft 29, into the space H of the same, and through the holes 39 and 40 of the shaft 29 and sleeve 32, respectively, into the exhaust pipe 41, leading to the condensator. By moving the lever 77 forward 30 35 and aft, either the shaft or the cylinder can be locked from rotation, or, when the clutch sleeve 78 is midway between the clutch sleeve 79 and the clutches 74, both are free to rotate. Correspondingly the extension shaft 40 45 91 is coupled either to the shaft 29, or to the sleeve 32, rotating with the cylinder 42, or else uncoupled from both. This extension shaft is only required when direct axial transmission is employed, as in ships and the like, whereas the engine itself, *i. e.* the cylinders with the pistons within, will serve as pulley if transmission by belting is employed. 50

Having thus described the preferred form of my invention, it is understood that I do not want to be limited to its mechanical details. Especially I wish to mention that instead of a double expansion compound construction I may employ a single cylinder construction, or else triple or quadruple expansion etc. Also in the construction of stationary engines the clutch coupling would be done away with, the shaft being rigidly mounted on supports and the cylinder 55 60 65 rotatably thereon, either as a belt pulley or directly coupled to dynamos, pumps or the like. Also the inlet and exhaust of steam into and from the hollow shaft can be made differently from those shown and described above.

Having thus described my invention, what I claim is:

1. A rotary steam engine, comprising, in combination, a substantially tubular shaft, divided at its longitudinal center into an inlet and an outlet compartment, the inlet end being open and abutting into an inlet chamber formed in a vertical support in which said open end of said shaft is rotatably mounted, said inlet chamber communicating through an inlet channel formed in said support with the steam supply pipe, the other end of said tubular shaft closed and rotatably mounted in a sleeve carried by another vertical support having an outlet channel formed therein, and an annular chamber surrounding said sleeve, an annular recess formed inside of said sleeve correspondingly to said annular chamber, ports of communication leading from the outlet compartment of said tubular shaft into the annular recess formed in said sleeve and therefrom into the annular chamber surrounding said sleeve, a cylinder having one head integral with said sleeve and the other head integral with a clutch-carrying sleeve, rotatably mounted on said tubular shaft, a cylinder casing intermediate said cylinder heads removably fastened thereto, a piston rigidly mounted on said tubular shaft within said cylinder, divided into an inlet- and an exhaust-chamber by a substantially vertical partition, said inlet chamber communicating through ports in said tubular shaft with the inlet compartment thereof and the exhaust chamber of said piston similarly communicating with the exhaust compartment of said tubular shaft, supply ports leading from said inlet chamber of the piston into the space between said piston and said cylinder-cover, exit ports leading from said space into the exhaust chamber of the piston, two bosses formed on the outer periphery of said piston at diametrically opposite points thereof, forming steamtight partitions in said space between the piston and cylinder-cover, said supply ports traversing said bosses, steamtight valve plates hingedly mounted in recesses formed in said cylinder cover, equidistantly from each other, normally held in a position by spring means to form steamtight partitions in said space between the piston and the cylinder-cover, but adapted to be pushed into said recesses formed in the cylinder cover by said bosses, spring means to mitigate the force of the impact between said valve plates and said bosses, and means coacting with said clutch-carrying sleeve integral with one cylinder-head for alternately locking from rotation either said cylinder or said tubular shaft, or releasing both. 70 75 80 85 90 95 100 105 110 115 120 125 130

2. A compound rotary steam engine comprising, in combination, a substantially tubular shaft divided at its longitudinal center

into an inlet and an outlet compartment, the inlet end being open and abutting into an inlet-chamber formed in a vertical support in which said open end of said shaft is rotatably mounted, said inlet-chamber communicating through an inlet-channel formed in said vertical support with the steam supply pipe; the other end of said tubular shaft closed and rotatably mounted in a sleeve carried by another vertical support having an outlet-channel formed therein and an annular chamber surrounding said sleeve, an annular recess formed inside of said sleeve correspondingly to said annular chamber, ports of communication leading from the outlet compartment of said tubular shaft into the annular recess formed in said sleeve and therefrom into the annular chamber surrounding said sleeve, a plurality of cylinders rotatably mounted on said tubular shaft, each successive cylinder larger than the preceding one in proportion of the expansion of steam passing from one into the other, the first of said cylinders having one head integral with a clutch-carrying sleeve rotatable on said tubular shaft and the last of said cylinders having one head integral with said sleeve carried by said vertical support, common heads between each two adjoining cylinders, cylinder-casings between each pair of cylinder-heads, bolts connecting the several cylinder-heads and cylinder-casings causing all the cylinders to rotate together, a piston rigidly mounted on said tubular shaft, with each of said cylinders, each of said pistons divided into an inlet and an exhaust-chamber by substantially vertical partitions, the inlet chamber of the first of said pistons communicating through ports in said tubular shaft with the inlet compartment thereof and the exhaust chamber of the last of said pistons similarly communicating with the exhaust compartment of said tubular shaft, supply ports leading from the inlet chambers of each piston into the space between

said pistons and said cylinder-covers, exit-ports leading from said spaces into the exhaust chambers of each piston, two bosses formed on the outer periphery of each of said pistons at diametrically opposite points thereof, forming steamtight partitions in said spaces between the pistons and the respective cylinders, said supply-ports traversing said bosses, steamtight valve-plates hingedly mounted in recesses formed in said cylinder-covers, equidistantly from each other, normally held in position by spring-means to form steamtight partitions in said spaces between the pistons and the respective cylinders, but adapted to be pushed into said recesses by said bosses, spring means to mitigate the force of impact between said valve plates and said bosses, ports through said intermediate cylinder-heads leading from the exhaust-chamber of each piston into the inlet-chamber of each successive piston, and means coacting with said clutch-carrying sleeve for alternately locking from rotation either said cylinder or said tubular shaft, or releasing both.

3. With a device of the character described, in combination, an extension shaft journaled in the bearing carried by the support at the exhaust end of the said shaft, said shaft having claws at its end adapted to be engaged by claws at the end of the said extension shaft and forming a clutch gear with same, the claws on the extension shaft being arranged around its outer circumference and adapted to become engaged with similar claws formed in the inside of a sleeve in connection with the cylinder and means connected with the aforesaid lever for coupling the said extension shaft to the main shaft or to the said sleeve of the cylinder or disconnecting it from both.
